UNITED STATES PATENT OFFICE.

JOHN B. WHITNEY, OF NEW YORK, N. Y.

DESIGN FOR DOOR-KNOBS.

Specification forming part of Design No. 6,361, dated January 21, 1873.

To all whom it may concern:

Be it known that I, JOHN B. WHITNEY, of the city, county, and State of New York, have invented a new and original Design for a Door-Knob, of which the following is a specification:

The accompanying engraving fully represents my new design.

This invention relates to a new ornamentation of the face and edge of a door-knob.

The face is composed of a central rosette, surrounded by a circular border, around which an annular space containing a succession of projecting ornaments of the form shown is observed. The rim or outer part of the knob

consists of a continuous line or rib, forming outwardly-projecting letters V with an inwardly-projecting loop between every pair of adjoining outward projections.

I claim as my invention—

1. The design for the face ornamentation of a door-knob, as shown.
2. The design for the ornamentation of the rim of a door-knob, as shown.

JOHN B. WHITNEY.
